BY *Richard Oliver,*

ATTORNEY

UNITED STATES PATENT OFFICE.

MORGAN J. LANGTON, OF OSWEGO, NEW YORK.

VALVE-LOCK.

1,302,933.

Specification of Letters Patent.

Patented May 6, 1919.

Application filed June 6, 1918. Serial No. 238,541.

To all whom it may concern:

Be it known that I, MORGAN J. LANGTON, a citizen of the United States, residing at Oswego, in the county of Oswego and State 5 of New York, have invented certain new and useful Improvements in Valve-Locks, of which the following is a specification.

This invention is a lock and has special reference to a valve lock.

10 One object of this invention is the production of a valve lock which includes a casing rotatably mounted upon the valve stem, thus preventing the stem from being engaged and operated by an unauthorized 15 party, since the casing will be free to rotate, although an operating mechanism is carried within the casing which is to be operated by a properly formed key which will conform to the combination of the structure, thus permitting a valve to be operated.

Another object of this invention is the production of a pair of normally spaced apart clutch plates having registering teeth, although the particularly formed key is inserted 25 through a perforated plate for engaging one plate and moving the same into engagement with the remaining plate, thus causing the teeth to engage, whereby as the key is swung in a circle, the plates will rotate the 30 valve stem for operating the valve.

One practical form of construction and assembly of the present invention will be hereinafter described and is illustrated in the accompanying drawing, in which—

35 Figure 1 is a side elevation of the combination valve lock as the same appears when in use.

Fig. 2 is an enlarged vertical section taken on the line 2—2 of Fig. 1, the valve stem being shown in elevation.

40 Fig. 3 is a section taken on the line 3—3 of Fig. 2 looking in the direction of the arrows.

Fig. 4 is a section taken on the line 4—4 of Fig. 2 looking in the direction of the arrows.

Fig. 5 is a section taken on the line 5—5 of Fig. 2 looking in the direction of the arrows.

Fig. 6 is a fragmentary plan view of the 50 key, and

Fig. 7 is a fragmentary sectional view through the key.

In the preferred embodiment of the present invention about to be described, 5 indicates the valve casing having a threaded nipple 4 extending therefrom which carries a nut 7 provided with a hollow neck 8. The valve stem 9 extends through the neck 8 and projects thereabove, as shown in Fig. 2. It will therefore be seen that the stem is shielded against tampering, as it extends through the neck 8.

The lock casing 10 has a cover 11 provided with ears 12 which ears 12 are retained in engagement with the casing 10 by the screws or other securing members 13. The sleeve 10' extends from the lower portion of the casing 10 and fits over the neck 8, as shown in Figs. 1 and 2.

The primary clutch plate 14 has an annular rim 15 upon its periphery. This clutch plate has a central opening 16 fitting over the squared end of the valve stem 9. This primary clutch plate 14 rests upon the inner portion of the casing 10, as shown clearly in Fig. 2. This primary clutch plate 14 is provided with an annular row of teeth 17 formed upon its surface and contiguous to the rim 15, as shown in Figs. 2 and 4.

The disk 18 bears upon the primary clutch 14 and the screw 19 passes through the plate into the upper end of the valve 9, thus holding the primary clutch plate 14 in engagement with the valve stem, since the plate 18 overlaps the primary clutch plate 14, thus holding the same against displacement. Flat springs 20 are fixed as indicated at 21 upon the disk 18 and extend for considerable distances beyond the surfaces of this plate, as shown in Fig. 2.

The auxiliary clutch plate 22 is positioned above the primary clutch plate 14 and this auxiliary plate 22 has teeth 23 formed upon its lower surface in alignment with the teeth 17 formed on the primary clutch plate 14. 95 It will be noted that the auxiliary clutch plate 22 rests upon the springs 20 of the disk 18, whereby the two clutch plates will be normally held separated.

A partition disk 24 rests upon the annular rim 15 of the primary clutch plate, while the auxiliary clutch plate 22 fits within the diameter of this annular rim, thus allowing the disk 24 to rotate upon the annular rim

15, while the auxiliary clutch plate will rotate in unison therewith, although the primary clutch plate will not rotate under such conditions.

5 Stems 25 extends through the disk 24 and are permanently connected to the auxiliary clutch plate at their lower ends while the bridge 26 is supported upon the upper ends of these stems 25.

10 It will be noted that coiled springs 27 surround these stems 25 and bear at their lower ends upon the disk 24 and at their upper ends upon the bar 26, thus forcing the bridge bar away from the disk 24 and holding the 15 auxiliary tumbler plate in close engagement with the disk 24.

The key plate 28 is carried upon the disk 24. This plate carries a plurality of perforated plates 29, as shown at 30; these perforations may take the form of numerals.

20 The cover 11 of the casing 10 has a ribbed strip 31 secured thereto in any desired manner and under normal conditions the bridge bar 26 is engaged by the ribbed clip 31, as 25 shown in Fig. 2.

It will be noted that this bridge bar 26 is provided with a guide groove 26' therein, as shown in Fig. 2, while it will also be noted that the casing 10 is provided with a 30 key opening 32 formed in its side, this key opening as herein illustrated, being substantially T-shaped. By referring to Figs. 6 and 7, the construction of the key will be disclosed. A body 33 has flanges 34 upon its 35 side edges, to allow the ward plates 35 to be slipped into engagement therewith, while the wards 36 are in the form of numerals formed on these plates 35. The plates 35 are held in position on the body 33 by a block 40 37. As the perforated plates 29 of the dial plates 28 are removable and the ward plates 35 of the key are removable, it is obvious these wards may be changed about to make various combinations.

45 Since the partition disks 24 rest upon the annular rim 15 of the primary clutch plate 14, it is obvious the tension of the springs 27 and the springs 20 of the disk 18 will hold the auxiliary clutch plate spaced from the 50 primary clutch plate. Therefore, if some unauthorized party inserts an implement and rotates the casing 10, it is obvious the bridge bar 24 and the auxiliary clutch plate will rotate in unison therewith. The primary plate however being keyed upon the upper end of the valve stem will not move and for this reason the valve stem will not be shifted for actuating the valve.

55 The notch in the bridge bar 26 serves to 60 guide the key 33 that the ward 36 of the key will register with the slots in the perforated plates 29. A downward pressure on the key will then cause the wards 36 to pass through the perforated plates 24 thus moving the 65 auxiliary tumbler plate 22 toward the pri-

mary tumbler plate 14, for moving the teeth 23 into engagement with the teeth 17.

The foregoing description and the drawings have reference to what may be considered the preferred, or approved, form 70 of my invention. It is to be understood that I may make such changes in construction and arrangement and combination of parts, materials, dimensions, et cetera, as may prove expedient and fall within the scope of 75 the appended claims.

Having thus fully described my invention, what I claim as new and desire to secure by Letters Patent, is:—

1. In a device of the class described, the 80 combination of a stem having a protector neck fitting thereover, a lock casing movably mounted upon said neck, a key opening in the side of said lock casing, and a latching means within said casing, whereby a key 85 may be inserted into the casing for actuating the locking means, although the side opening in the casing prevents an accurate view of the latching means.

2. In a device of the class described, the 90 combination of a stem having a protector neck thereon, a lock casing movably mounted upon said neck, a primary clutch plate fixed upon said stem, an auxiliary clutch plate yieldably held above the primary clutch plate, perforated means above the auxiliary clutch plate, whereby a properly formed key may be inserted into the casing and then passed through the means to move the auxiliary clutch plate 100 into engagement with the primary clutch plate so that as the lock casing is turned, said stem may also move.

3. In a device of the class described, the 105 combination of a stem having a protector neck thereon, a lock casing movably mounted upon said neck, the primary clutch plate fixed upon said stem, an auxiliary clutch plate, means for yieldably holding said clutch plates separated, a key plate having a plurality of perforated plates, whereby a properly formed key may be inserted into the casing and passed through the perforated plates toward the auxiliary clutch plate and bring the auxiliary clutch plate 110 into engagement with the primary clutch plate and thus as the lock casing is turned, said stem will be rotated.

4. In a device of the class described, the 120 combination of a stem having a neck thereon, a lock casing movably mounted upon said neck, a primary clutch plate fixed upon said stem, and having an annular rim on its periphery, a partition resting upon said rim, an auxiliary clutch plate positioned below said partition disk, means for holding said plates separated, a key plate carried by said partition, and having a plurality of perforated plates, guide means carried within said casing to direct a properly formed key 125 130

through the openings in said perforated plates, thus causing the key to engage the auxiliary clutch plate and move the same into engagement with the primary clutch plate, whereby as the casing is rotated, said

5 stem will be turned.

In testimony whereof I affix my signature in presence of two witnesses.

MORGAN J. LANGTON.
